UNITED STATES PATENT OFFICE.

THOMAS E. FEARON, OF PHILADELPHIA, PENNSYLVANIA, ASSIGNOR TO THE MILLER, DU BRUL AND PETERS MANUFACTURING CO., OF CINCINNATI, OHIO, A CORPORATION OF OHIO.

HOLDER FOR CIGARS IN PACKAGES.

1,243,827.

Specification of Letters Patent. Patented Oct. 23, 1917.

Application filed October 25, 1916. Serial No. 127,643.

To all whom it may concern:

Be it known that I, THOMAS E. FEARON, a citizen of the United States, residing at and whose post-office address is 1510 North 5 Gratz street, Philadelphia, Pennsylvania, have invented a certain new and useful Holder for Cigars in Packages, of which the following is a specification.

The present invention relates to a holder 10 for cigars that will sustain them in position when some of the cigars have been removed from a package, particularly, a package in which the cigars stand on end. The invention has for its object to provide an inexpensive means for effectively accomplishing 15 this purpose, and particularly one that may be made from a single sheet of paper or other cheap material.

The essential characteristics of a device 20 of this kind are stalls or pockets to receive the cigars, preferably a separate pocket for each cigar, and the capacity, in the holder, to sustain itself and the cigars in upright position after any number of cigars are removed. The present invention solves the 25 problem and embodies these essential characteristics in a holder made of a single sheet of paper, by merely splitting the paper at intervals along an intermediate zone to provide 30 straps which, while remaining integral with the sheet of paper at their respective ends, are separated therefrom along their lateral edges for a sufficient distance to enable each strap to be looped or arched outwardly from the plane of the paper and form a pocket to receive a cigar. As this loop or arch of the strap-forming portions 35 of the paper necessarily contracts the paper longitudinally, the resultant fullness in the zones or longitudinal strips of paper on either side of the strap forming portions, is gathered, fluted or plaited, and when thus formed, these gathered portions are in condition to serve as confining walls for the 40 cigars, opposing the walls provided by the strap-forming portions. The gathering of the portions of the paper sheet forming said opposing walls develops resiliency and pro-

duces a shock absorbing structure which serves to protect the cigars against injury 50 in transportation or manipulation of the package. Moreover, the cigar packing holder constructed as described, is flexible in the highest degree and especially well adapted for rolling its contained cigars into 55 a bundle of cylindrical or other form.

In order that the invention may be fully understood, a detailed description will now be given of one illustrative embodiment thereof, in connection with the accompanying drawing, in which—

Figure 1 is a side elevation, partly in section, of a cigar package made up in part of a packing holder embodying the invention;

Fig. 2 is an edge view of a portion of the 65 packing holder, and

Fig. 3 is a face view of the same.

In producing the new packing holder, a sheet of paper 1 is slit at intervals along opposite edges of an intermediate longitudinal zone, as illustrated at 2; to provide pocket-forming straps 3; unslit portions 4 being left to maintain the connection of these straps with the sheet or main body of the holder. The straps 3 are arched outward as shown in Fig. 2 and so form pockets 5 for the cigars; the end zones 6 of the original sheet, necessarily left with fullness by the arching of the straps being fluted, plaited, or otherwise treated to take up the fullness, and they are thus adapted to serve as base walls opposing the walls formed by the straps and thus completing the pockets. The fluting or gathering of the base of the sheet, adapts the packing holder to roll into 85 a cylindrical or other form of bundle, inasmuch as it is not only highly flexible, but yielding to both compression and tension in the longitudinal direction of the sheet.

I claim:—

1. A packing holder for cigars or the like comprising a sheet of material slit at intervals along an intermediate longitudinal zone and having the straps thus formed, deflected to provide pockets and the longitudinal portions of the sheet lying on either side of said

90

95

straps, gathered and forming base walls opposing the strap walls in the confinement of articles in the pockets.

2. A packing holder for articles of merchandise comprising arched straps arranged along an intermediate longitudinal zone of the holder and longitudinal zones of gathered material arranged on either side of the

strap zone, the arched straps and the gathered material forming pockets to receive the articles to be packed.

The foregoing specification signed at Philadelphia, Pennsylvania, this sixth day of Oct., 1916.

THOMAS E. FEARON.
